DESIGN FOR A MEMORANDUM RECORDING DEVICE

Ray W. Lambert, Chicago, Ill.

Application August 5, 1939, Serial No. 36,483

Term of patent 14 years

To all whom it may concern:

Be it known that I, Ray W. Lambert, a citizen of the United States, residing at Chicago, in the county of Cook and State of Illinois, have invented a new, original, and ornamental Design for a Memorandum Recording Device, of which the following is a specification, reference being had to the accompanying drawing, forming part thereof.

Fig. 1 is a plan view of a memorandum recording device showing my new design.

Fig. 2 is an elevation of one side of a memorandum recording device showing my new design.

Fig. 3 is an elevation showing the other side of a memorandum recording device showing my new design.

Fig. 4 is a rear end elevation of a memorandum recording device showing my new design.

I claim:

The ornamental design for a memorandum recording device, as shown.

RAY W. LAMBERT.
